[57] CLAIM

The ornamental design for a credit card reader, as shown and described.

DESCRIPTION

FIG. 1 is a top, front, right side perspective view of a credit card reader showing my new design;

FIG. 2 is an enlarged right side elevational view thereof;

FIG. 3 is an enlarged top plan view thereof;

FIG. 4 is an enlarged rear elevational view thereof.

The opposite side elevational view and the bottom plan view are flat and unornamented.

FIG. 1

FIG. 2

FIG. 3

FIG. 4
